(57) **CLAIM**

The ornamental design for a sandal, as shown and described.

DESCRIPTION

FIG. 1 is a perspective view of a sandal showing the new design;

FIG. 2 is another perspective view thereof;

FIG. 3 is a left-side elevation view thereof;

FIG. 4 is a right-side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged view of the encircled portion labeled “9” in FIG. 8.

The dot-dash lines in FIGS. 8 and 9 are used to annotate an area of enlargement and form no part of the claimed design. The dashed seam edge lines shown on the sandal straps depict stitching in FIG. 8, which does form a part of the claimed design. The broken lines showing the remainder of the sandal show portions that form no part of the claimed design.
